(57) CLAIM

The ornamental design for a bowl, as shown and described.

DESCRIPTION

FIG. 1 is a top, perspective view of a bowl showing my new design;

FIG. 2 is a side view thereof;

FIG. 3 is a top view thereof; and,

FIG. 4 is a bottom view thereof.

The broken lines which define the bounds of the claimed design in FIGS. 2 and 4 form no part thereof.

In FIGS. 1 and 3 the uniform shading inside the bowls indicates a contrasting color with the remainder of the bowls, however no particular color is being claimed.
